(57) **CLAIM**

The ornamental design for ladder platform, as shown and described.

DESCRIPTION

FIG. 1 is a perspective view of a ladder platform showing our new design with an adjustable bumper stand-off; and, FIG. 2 is a perspective view thereof wherein the bumper stand-off is shown with arrows indicating the direction of adjustment and a ladder is shown in broken lines as it is not a part of this invention and is shown for illustrative purposes only.

1 Claim, 2 Drawing Sheets

FIG 1

FIG 2
